UNITED STATES PATENT OFFICE.

JOHN ADAMS AND BENNO SCHAEFFER, OF HOBOKEN, NEW JERSEY.

COMBINED STEM, PIPE, AND CIGAR HOLDER.

1,316,472.

Specification of Letters Patent. Patented Sept. 16, 1919.

Application filed November 13, 1917. Serial No. 201,737.

To all whom it may concern:

Be it known that I, JOHN ADAMS, a citizen of the United States, resident of Hoboken, county of Hudson, and State of New Jersey, and I, BENNO SCHAEFFER, a subject of the Emperor of Germany, resident of Hoboken, county of Hudson, and State of New Jersey, have invented certain new and useful Improvements in Combined Stems, 5 Pipes, and Cigar Holders, of which the following is a specification.

This invention relates to improvements in mouthpieces of pipe stems and cigar holders and has as its special object the provision of a mouth piece which may be attached either to the stem of a pipe or used to support a cigar with equal facility.

A further object is to provide means combined with the mouthpiece whereby the cigar 20 may be securely clamped so as to prevent the same from becoming loosened and inadvertently dropping from the holder, and finally to provide a mouth stem which may be particularly suited to the requirements of the 25 user in combination with an adapter so that it may be used for either purpose.

These and other like objects are attained by the novel construction and combination of parts hereinafter described and shown in 30 the accompanying drawings, forming a material part of this specification, and in which:

Figure 1 is a side elevational view, showing the application of the mouthpiece to 35 a pipe of ordinary construction.

Fig. 2 is a longitudinal sectional view taken through the center of the same.

Fig. 3 shows the device as applied to a cigar.

In the drawings, the numeral 10 is applied 40 to the pipe bowl which is provided with a usual stem 11, through which is a central axial passage 12, for the smoke, the stem terminating in a conical end 13. The mouthpiece 45 has a central passage 16 for the smoke and may be made of such shape as is best adapted to the requirements of the user. The end which is held in the mouth preferably has a flattened conical surface 50 adjoining a stem 18, terminating in a thread-

ed end 19, fitted to be received at either end within a central cylindrical sleeve 20, having one conical internally threaded end 21, suited to engage with the threads of the stem 13 of the pipe, while the opposite end 55 22 is extended outwardly presenting a hollow cone adapted to receive the end of a cigar in the usual manner.

When used in connection with a pipe, the smaller coned end 21 is engaged in an obvious manner, while if it be used as a cigar holder, the threaded portion 19, is unscrewed from the sleeve 20 and reentered from the opposite direction, so as to present the opening 22 outwardly.

Formed in the enlarged coned end 22 are a plurality of slits 24, the same presenting fingers 25, of resilient nature, adapted to engage with a cigar 30 as indicated in Fig. 3, and in order to hold the same securely, 70 an outer sliding sleeve 26 is arranged upon the inner sleeve 20, so that the same can be pressed toward the cigar, causing the fingers 25 to securely clamp upon its outer surface.

Having thus described our invention, what 75 we claim as new and desire to secure by Letters Patent, is:—

In combination, a pipe stem having a tapering end, a mouthpiece provided with an elongated, threaded tapering portion, a tapering, cylindrical sleeve having flaring hollow portions formed at the opposite ends thereof, the inner portion of said cylindrical sleeve beyond its center being short and threaded for the reception of the tapered 85 portions of said mouthpiece on one side of its center and of said stem on the opposite side of its center, said sleeve at one of its end portions being formed with a series of slits, so as to provide fingers, and a cylindrical locking sleeve adapted to compress said fingers and being slidable over the other sleeve, and held against longitudinal displacement by the flaring portions of said last named sleeve.

In testimony whereof we have affixed our signatures.

JOHN ADAMS,
BENNO SCHAEFFER.
